T. WHITE.

HEATING STOVE.

No. 16,990.

Patented Nov. 16, 1886.

UNITED STATES PATENT OFFICE.

THOMAS WHITE, OF QUINCY, ILLINOIS.

DESIGN FOR A HEATING-STOVE.

SPECIFICATION forming part of Design No. 16,990, dated November 16, 1886.

Application filed October 20, 1886. Serial No. 216,776. Term of patent 7 years.

To all whom it may concern:

Be it known that I, THOMAS WHITE, of Quincy, in the county of Adams and State of Illinois, have invented and produced a new and original Design for a Heating-Stove, of which the following is a full, clear, and exact description.

This design embraces new and distinct parts and combinations of parts which make up the whole design, as hereinafter described, and pointed out in the claims.

Reference is to be had to the accompanying photograph, which forms part of this specification, and which represents a view in perspective of a heating-stove embodying my new and original design.

A distinguishing feature of this design is the shape and ornamentation of the portions marked A, B, C, and D.

20 The design for the top A consists of the convexly-curved upper molding, *a*, having the series of ornaments *a' b' c'*, the plain outer rim, *b*, and the concaved molding *e*, having the series of ornaments *e'*.

25 The design for the body portion B comprises the convexly-curved panel-like portion *f*, having within it the partly circular and straight side branch ornamentation, *g'*, containing a band, *h'*, and ornaments *i' k' l'*, and outside of these the ornaments *m'*. Said portion B is also decorated outside of the panel *f* with vertical rows of ornaments *n'*.

The design for the upper door or portion, C,

consists of a convexly-curved main face portion having parallel sides with line ornamentations *o'* on its surface and leaf and floral ornaments *r' s'*. 35

The design for the door or portion D consists of a convexly-curved face portion having parallel sides, with rectangular spaces *t'* in its 40 surface and the ornaments *u'* on the portions between and inclosing said spaces.

I claim—

1. In a design for a stove, the shape and ornamentation of the portion consisting of the 45 parts A B C D, as set forth.

2. In a design for a stove, the shape and ornamentation of the top A, consisting of the parts *a*, *d*, and *e*, as shown and described.

3. In a design for a stove, the configuration and ornamentation of the body portion B, with its panel-like portion *f*, as shown and described.

4. In a design for a stove, the shape and ornamentation of the door C next below the concaved molding *e*, as shown and described. 55

5. In a design for a stove, the configuration of the door D, having the rectangular spaces *t'* and the ornaments *u'* on the portions between and inclosing said spaces, as shown and described. 60

THOMAS WHITE.

Witnesses:

THOMAS C. WHITE,
HENRY WILSON.
